UNITED STATES PATENT OFFICE.

JOSEPH A. NONES, OF NEW YORK, N. Y.

DESIGN FOR A DISPLAY-STAND.

49,366.

Specification for Design.

Patented July 11, 1916.

Application filed May 3, 1915. Serial No. 25,611. Term of patent 3½ years.

To all whom it may concern:

Be it known that I, JOSEPH A. NONES, a citizen of the United States, residing at New York city, in the county and State of New York, have invented a new, original, and ornamental Design for Display-Stands, of which the following is a specification, reference being had to the accompanying drawing, forming part hereof.

play stand, showing my new design. Fig. 2 is a side elevation of the same; and Fig. 3 is a plan view of the same.

I claim:

The ornamental design for a display stand, as shown.
